Specification of Letters Patent. Patented Sept. 5, 1916.

Application filed September 25, 1915. Serial No. 52,546.

To all whom it may concern:

Be it known that we, CHARLES B. KING, CHARLES S. JOHNSON, and BENJAMIN JACOBY, citizens of the United States, residing at 5 Marion, in the county of Marion and State of Ohio, have invented certain new and useful Improvements in Excavating-Machines, of which the following is a specification, reference being had therein to the accompanying drawing.

This invention relates to excavating machines and more particularly to an excavating machine of the steam shovel type utilizing an internal combustion engine as its 15 source of power. It is well known that steam shovels commonly employ a plurality of individual engines for operating the several parts of the mechanism. There is an engine to operate the hoisting mechanism, another to operate the swinging mechanism, and a third on the boom to operate the crowding mechanism. The character of the steam engine is such that these engines can be located at points remote from the operator 20 and readily controlled and because of their flexibility they are well adapted for this work. The power can be regulated according to the load and the engines can be readily reversed. With a gas or internal combustion engine the crank shaft rotates continuously in one direction, that is, it is not reversible, it cannot be as readily started as a steam engine can, and under excess of load will choke down and stop, and it is 25 necessary to relieve it of its load before it can be again started. Because of these characteristics of the gas engine it cannot be utilized in the same manner that a steam engine is utilized.

40 The object of the present invention is to provide an excavating machine in which a single gas engine will be utilized to drive the various parts of the mechanism and the power will be so distributed and controlled 45 as to enable these various parts to be operated and controlled in substantially the same manner in which they are operated and controlled by the individual steam engines.

To this end it is a further object of the 50 invention to provide means for operating the crowding mechanism on the boom from a crowding shaft on the main platform. It is also an object of the invention to provide means for automatically relieving the en-

gine from an excessive load, thereby avoiding the choking down of the engine.

It is also an object of the invention to so construct and organize the machine as a whole that it will be very compact in its arrangement; that the several parts thereof 60 will be readily accessible; that it will be of a strong, durable character with no parts liable to be broken or disarranged; and that it can be constructed at a low cost.

In the accompanying drawings, Figure 1 65 is a side elevation of an excavating mechanism embodying our invention; Fig. 2 is a top, plan view of such a mechanism with the boom removed; Fig. 3 is an enlarged plan of a portion of the handle operating gears, 70 the handle being shown in section; Fig. 4 is a sectional plan view showing the driving connections from the engine and the reversing clutches; Fig. 5 is a detail side elevation of the clutch band operating and connecting devices; Fig. 6 is a section on the line xx of Fig. 5, looking in the direction of the arrows; Fig. 7 is a side elevation of the reversing gear and brake drum operating lever devices; Fig. 8 is a plan thereof showing the operating devices in neutral position; Fig. 9 is a similar view showing the 75 position of the device when one of the brake bands is in engagement with its drum; Fig. 10 is a transverse, vertical section through 80 the hoisting drum and associated parts; Fig. 11 is a plan view showing the controlling mechanism for the crowding mechanism; Fig. 12 is a detail view showing in front elevation the brake band of Fig. 11; 90 and Fig. 13 is a side view, partly in section, of the mechanism shown in Fig. 11.

In these drawings we have illustrated the invention as applied to a power shovel of a well known type. The mechanism comprises 95 a truck having a base 1, traction wheels 2 and steering wheels 3. Rotatably mounted upon the truck is a platform 4 at the forward end of which is pivotally mounted a boom 5 carrying the excavating device, 100 which, in the present instance, is in the form of a dipper 6 carried by a handle 7 extending transversely of the boom 5, between the two members thereof, and provided on its rear edge with a toothed rack 8 which 105 meshes with a pinion 9 on a shipper-shaft 10 journaled on the boom. Mounted on the opposite ends of the shipper-shaft are gears

11 meshing with pinions 12 carried by a countershaft 13 on which is mounted, preferably between the pinions 12, a bevel gear 14 meshing with a bevel pinion 15 carried by one end of a shaft 16 extending lengthwise of the boom and journaled in suitable bearings 17 which are here shown as formed in brackets 18. This mechanism comprises a crowding mechanism for the dipper and serves to impart longitudinal movement to the dipper handle 7, whereby the dipper is moved toward or away from the work. The dipper is elevated, to fill the same, by means of a cable 19 which extends about sheaves 20 on the end of the boom and passes lengthwise of the boom to a hoisting drum 21 mounted on a shaft 22 on the platform 4. In order to bring the dipper into proper position with relation to the work, that it may be filled, and to then convey the dipper to the point at which it is to be dumped, the platform 4 is revolved about its axis. This is accomplished by providing the base 1 of the truck with a fixed gear or annular rack 23 with which meshes a pinion 24 mounted on a short shaft 25 to which is secured a gear 26 meshing with a pinion 27 on the lower end of a shaft 28 arranged vertically in the platform 4 and having at its upper end a bevel gear 29.

The main features of construction, as heretofore described, do not differ materially from the standard shovels. Such differences as may be noted are for the purpose of accommodating the device to the present invention and enter into co-operation with the mechanism to be hereinafter described.

Mounted on the rear portion of the platform, that is, that portion opposite the boom 5, is an internal combustion engine 30 which may be of any suitable type and is here shown as a four cylinder engine of a standard construction. On either side of the engine are water tanks 31 for the water cooling system, the connecting pipes having been broken away. The fuel tank is not shown but may be arranged in any suitable location. Preferably, because of the crowded condition of the platform, it will be placed beneath the platform and a suitable feeding device provided in connection therewith, but this forms no part of the present invention and does not need to be illustrated. The crank shaft 32 of the engine extends forwardly and is journaled in a bearing 33 mounted upon the platform or main supporting frame 4. Interposed between the bearing and the end of the engine is the usual fly wheel 34. A bevel pinion 35 rigidly secured to the end of the engine shaft 32 meshes with two opposed bevel pinions 36 and 37 loosely mounted on a shaft 38 extending transversely of the platform 4 and journaled in bearings 39. This shaft may be

termed the main shaft or reversing shaft because not only does it serve as the medium through which the power is transmitted from the engine to all of the parts of the mechanism but it also is reversible and serves as the reversing shaft for certain parts of the mechanism, such as the propelling devices, as will be hereinafter described. To this end means are provided for clutching either of the bevel gears 36 or 37 to the shaft while its companion gear is allowed to run idle, and there is provided a suitable controlling device for this clutch mechanism, whereby the one gear will be automatically released before the other is clutched to the shaft. The clutch mechanism, as herein shown, comprises two friction drums 40 and 41 mounted upon and rigidly secured to elongated hubs 43 forming part of the respective gears 36 and 37. Rigidly secured to the shaft adjacent to the friction drums 40 and 41 are two supports 44 and 45, here shown in the form of wheels or spiders. Carried by these supports are friction bands 46 and 47 which extend about the respective friction drums 40 and 41 and are secured at their ends to their respective supports. Means are provided on each support for tightening or loosening the band about the friction drum and, to this end, one or both of the ends of the friction band are adjustably connected with the support. In the present construction two studs or short shafts 48 and 49, Fig. 5, are rotatably mounted in each support and each shaft is provided on its inner end with a crank arm 50 having a pin or trunnion 51 to which the ends of the friction band are connected.

Fig. 4 shows the crank arm 50 and pin 51 in connection with the stud 49. The arrangement is the same on the stud 48, although not shown. It is thought that the structure will be clear. The crank shaft, 48, is held normally against movement and, to this end, is provided with a crank arm 51' having connected to its outer end one end of a rod 52, the other end of which is slidably mounted in an apertured lug 53 secured to the support 44 or 45. Confined between the lug 53 and a shoulder 54 on the rod 52 is a spring 55 of such strength that it will normally hold the crank arm 51' and the shaft 48 against movement in one direction, the rod being held against movement in the other direction by a nut 56. Means are provided for manipulating the other crank arm and shaft to tighten or loosen, as may be desired, the friction band. As here shown, this other crank shaft, 49, is also provided with a crank arm 57 to the outer end of which is connected a link 58, the opposite end of which is pivotally connected to two other links, one of which, the link 59, is pivotally connected to a fixed part of the support, as to one of the spokes thereof. The 130

second link, 60, which is connected with the link 58, forms a part of a toggle and is pivotally connected with a link 61 which forms the other part of the toggle and which is pivotally mounted at 62 upon the hub of the support. Rigidly secured to the inner arm of the toggle, 61, and extending through a slot 63 in the hub of the support 44 is an arm 64, the inner end of which extends into an opening or slot 65 formed in a plunger or slide rod 66 which is slidably mounted in an axial opening 67 formed in one end of the shaft 38 and slideable therein. Obviously, the reciprocation of the plunger 66 will 5 break or straighten the toggle 60-61, thus rocking the crank shaft 49 and tightening or loosening the brake band. When the toggle is in its extended or straightened position the brake band will be in its tightened condition and will be held very rigidly in that position because the several axes of the toggle are in alinement, or preferably the central axis will have been moved slightly beyond the axes of the ends of the toggle. There 10 are, of course, two of these plungers 66, one mounted in each end of the shaft, and the two plungers are preferably operated successively the one to straighten its toggle and tighten its clutch band and the other to break its toggle and release its clutch band. Further, it is desirable that this operation be accomplished from a remote point, such for example, as the forward end of the platform, at which point the operator stands. 15 To this end the two plungers are connected one to the other and an operative connection is established between the one plunger and an operating lever. These connections may be established in various manners but 20 that shown in Figs. 2, 7, 8 and 9 is a very efficient one. As there shown controlling lever 69, which is located at the forward end of the platform 4, is connected at its lower end with a rod 70, which, in turn, is connected with an arm 71 mounted on one end of a shaft 72 extending transversely of the platform and having at its other end a second arm 73 which is connected by means of a link 74 with an arm 75 secured to the 25 lower end of a vertical shaft 76 mounted in suitable bearings 78 near the end of the reversing shaft 38. A similar shaft 79 is mounted at the opposite end of the main or reversing shaft 38 and the shafts, 76 and 55 79, are provided, respectively, with arms 80 and 81 which are connected one with the other by a rod 82. Each of the vertical shafts 76 and 79 is provided at its upper end with an arm, or preferably a pair of 30 arms, 83, having in their ends slots 85 adapted to receive trunnions 86, as shown in Figs. 2 and 5, projecting from the outer end of the respective plungers 66, thereby establishing an operative connection between the controlling lever 69 and the two plungers. 35

The connections between the plungers and the controlling lever are such that the movement of the lever from its neutral position in one direction will actuate the selected plunger only and will allow the other plunger to remain idle, and further, this connection is such that when the lever is released the plunger will be automatically moved in a direction to release its clutch band. To this end, each of the arms 83 is rotatably mounted on its shaft and is provided with a slot or key-way 87 to receive a key 88 rigidly secured to the shaft. The key-way is of a length greater than the thickness of the key thereby allowing a certain amount of 40 lost motion and, consequently, the shaft can have movement relatively to the arm, a spring 89 being provided for each arm 83 to move the same independently of its shaft. There is one of these springs arranged about 45 the hub of each arm 83, as shown more particularly in Figs. 7 and 8, and the spring is secured at one end to the hub, as shown at 90, and at the other end to a pin 91 rigidly secured to a fixed part adjacent to the hub 95 of the arm.

On account of the construction of the key-ways in the arms 83 and the shafts 76 and 79, there is in reality no connection between these parts in certain positions and the springs are counted on to impart the movement to the arms. When the arms are in their neutral positions, as shown in Fig. 8, the movement of the connecting rod 82 in the direction of the arrow will cause the key 88 to be engaged with the side of the key-way in the arm 83 on the shaft 76, the arm turning with the shaft 76 and of course setting the friction. At the same time the shaft 79 will rotate but no motion will be given the arm 83 on the shaft 79 as in this position the key 88 in the shaft 79 has no contact with its arm 83. Therefore, the arm 83 on the shaft 79 will remain stationary, as the key does not move through an arc greater than the length of the key-way in the arm. After the arm 83 on the shaft 76 has been moved to its "in" or clutched position and it is desired to release the same, the connecting rod 82 is moved in the opposite direction, but as there is then no contact between the key 88 and the arm 83 on the shaft 76 in this direction, the spring must impart the motion to the arm 83 and throw out the clutch. In case the arm 83 should stick for some reason, then after the key 88 has rotated through the full width of the key-way in the arm 83, it would engage the side of the key-way in the arm 83 and give the arm a start; the spring throwing it out the remainder of the way. This feature of having the spring do the throwing out permits of the arms 83 having but half the travel that would be necessary in case the arms were keyed solid. 100 105 110 115 120 125 130

to the shaft. If the arm 83 were keyed solid to the shaft then it would be necessary to provide sufficient throw to allow one side to be completely thrown out before the other side was commencing to throw in, but with the present arrangement the two arms act independent of each other, that is, with the arms in neutral position no motion is imparted to the right hand arm while the left hand arm is being thrown either in or out, or vice versa. This is on account of the long key-way in the arm 83, as the amount of travel necessary to throw the arm 83 on the shaft 79 to "in" position is no greater than the amount of travel of the shaft 76 before it strikes the opposite side of the key-way in the arm 83. With the arm 83 on the shaft 79 thrown to "in" position, the key 88 would engage the side of the key-way, as shown, then in throwing this arm out the spring would cause the arm to follow the key until the arm 83 reached the "out" position, when the arm 83 would stop, but if the motion of the shaft 79 was continued in the same direction, which would be the case in setting the arm 83 on the shaft 76, the key 88 in the shaft 79 would simply turn through the key-way until it reached the opposite side of the key-way, by which time the arm 83 on the shaft 76 would be in "in" position. After the spring has moved the arm to "out" position the travel of the plunger will prevent any further movement thereof.

It will be apparent that the mechanism for driving and controlling the main or reversing shaft from the continuously rotating engine shaft is such that this shaft can be caused to rotate in either direction or to remain stationary and further that under an excessive load which would tend to choke down the engine the spring 55 will yield and permit the friction drum to rotate relatively to the friction band and, consequently permitting the engine shaft to rotate relatively to the driving shaft 38, thereby enabling the load either to be picked up gradually or to give the operator an opportunity to relieve the machine of its load, or a part thereof, without stopping the engine.

Extending transversely of the platform immediately in front of the main or reversing shaft 38 is a second transverse shaft 92 which is mounted in bearings 93 and is connected with and serves to operate the swinging mechanism and the bull pinion 24. This shaft is connected with the shaft 38 by means of a gear 94 rigidly secured thereto and meshing with a gear 95 rigidly secured to the main shaft 38. Consequently, the shaft 92 will be controlled by the movement of the shaft 38. This shaft 92 is provided near its outer ends with gears 96 and 97 which mesh, respectively, with pinions 98 and 99 on short shafts 100 and 101 having at their

inner ends bevel pinions 102 and 103 which mesh with the bevel gear 29 which is connected through the gears 27 and 26 with the pinion 24, which latter is adapted to travel about the fixed annular rack or gear 23 and 70 impart swinging movement to the platform and boom. The gears 96 and 97 are, of course, loosely mounted on the shaft 92 and are adapted to be individually connected thereto. To this end each gear has rigidly secured thereto and preferably mounted on the hub thereof a friction drum 104 about which extends a friction band 105 which is connected with a support 106 in substantially the same manner as described in connection with the 80 clutches on the reversing shaft 38. Further, the clutch bands are manipulated by mechanism substantially similar to that shown and described in connection with said reversing shaft. In the present instance, the controlling lever for the swinging mechanism is shown at 107 and is connected by a rod 108 to a short transverse shaft 109 and by a second rod 110 with a crank arm 111 which is connected with an operating mechanism 90 for the brake bands similar to that described, it being noted that the operating mechanisms for the two clutch bands are connected one to the other by a connecting rod 112 similar to the rod 82 which connects the controlling devices for the clutches of the reversing shaft. Thus, it will be apparent that the swinging mechanism may be controlled to cause the boom to be swung in either direction independently of the direction of movement of the main shaft 38.

Rigidly secured to the shaft 92 is a pinion 113 which meshes with a gear 114 rigidly secured to the shaft 22 also extending transversely to the platform and having loosely mounted thereon the hoisting drum 21 about which is wound the hoisting cable 19 for the excavating device or dipper 6. This hoisting drum is provided with a portion constituting a friction drum, as shown at 117, and a friction band 118 extends about the friction drum to connect the hoisting drum with and disconnect the same from the shaft. As under normal conditions of operation it is only necessary that the hoisting drum should be positively rotated in one direction it is provided with a single clutch device for connecting it with the shaft. When released it is turned in the other direction by the weight of the dipper as the latter descends. Suitable brake mechanism is usually provided to control this movement of the drum, but this forms no part of the invention and is not here shown. The hoisting drum shaft 22 is also utilized for actuating the propelling devices for the truck. To this end it is provided at one end with a gear 119 which is loosely mounted thereon and which meshes with a gear 120 on a shaft 121, to the inner end of which is secured a bevel pinion 122 meshing

with a bevel gear 123 secured to the upper end of a vertical shaft 124 extending through the platform and base of the truck, centrally of the annular rack 23, and having at its lower end a bevel pinion 125 meshing with a gear 126 on the propelling shaft 127 which is geared to the traction wheels in the usual manner. The gear 119, which is loosely mounted on the hoisting drum shaft 22, is adapted to be connected thereto by means of a clutch mechanism, and as here shown the gear 119 is provided with a tapered clutch housing 128 having an internal friction surface adapted to be engaged by a movable clutch member 129 which is slidably mounted on but keyed to the shaft 22 and is provided with a grooved collar to receive a yoke 130 of an actuating lever. This lever is shown at 131, Fig. 2, and is connected with the clutch member by means of a rod 132 which is connected by means of a bell crank lever 133 with a transverse rod 134 which is connected with the yoke 130. Thus, the propelling mechanism is controlled independently of the hoisting mechanism, the hoisting drum being preferably controlled by an overhead lever 135 which is connected through a vertical shaft 136 with clutch band operating devices similar to those heretofore described.

During the digging operation of the shovel the lever 69 is thrown ahead. With the lever 69 in this position the friction band 46, Fig. 4, is set giving the proper rotation to the machinery for the hoisting, swinging and crowding operation and for the forward propelling movement. When the drum 21 is clutched to its shaft this will also give the proper movement to the drum to raise the dipper. When either the drum or the gear 119 which communicates motion to the propelling mechanism is clutched to the shaft 22 the rotation thereof can be reversed by reversing the rotation of the reversing shaft 38, as described above. The reversing of this shaft is accomplished by throwing the lever 69 back.

Power is transmitted through the hoisting drum shaft 22 to the crowding mechanism 50 and to this end the gear 114, which is keyed to the shaft 22, meshes with a pinion 137 keyed to a shaft 138 extending transversely of the platform and having at its other end a gear 139 which meshes with a gear 140 on the crowding shaft 141 which extends transversely of the platform near the base of the boom. Loosely mounted on this shaft are two bevel gears 142 and 142' meshing with a bevel pinion 143 secured to the lower end 60 of the shaft 16 which actuates the shipper shaft on the boom. The gears 142 and 142' are provided with clutch devices 144 and 145 by means of which either of them may be secured to the shaft and actuated. The mechanism for controlling the gears 141 and

142 on the crowding shaft 141 is substantially the same as that for controlling the gears 36 and 37 on the main or reversing shaft 38 and need not be further described. The controlling lever for the crowding mechanism is shown at 146 and means are provided for locking the crowding mechanism against movement when this lever is in its normal or intermediate position. To this end the shaft 16 is provided with a brake drum 147 about which extends a brake band 148. The ends of this brake band are connected to the opposite arms of a bell crank lever 149 which is mounted on the upper end of a shaft 150 extending substantially parallel with the shaft 16 and provided at its lower end with a crank arm 151, which is here shown as a double arm. Connected with the arm 151 is one arm 152 of a toggle, the other arm 153 of which is rigidly secured to a transverse shaft 154 on which the controlling lever 146 is mounted. The arrangement of the toggle with relation to the lever is such that when the latter is in its normal position the toggle will be straight and the brake band 148 drawn snugly about the brake drum 147, thus locking the shaft 16 against rotation. When the lever is moved in either direction the toggle is broken and the brake band released. The rod 154 extends transversely to the platform and is provided at that end opposite the lever 146 with an arm 155 which is connected by a link 156 with an arm 157 which is rigidly secured to a vertical shaft 158 forming a part 100 of the clutch controlling mechanism for the crowding shaft. This vertical shaft is connected by means of an arm 159, rod 160 and arm 161 with a second vertical shaft 162 of said clutch controlling mechanism, which, as has been stated, is in other respects similar to the clutch controlling mechanism for the clutches on the shaft 38.

The term "adjusting device" as used in connection with our combined reversing devices and locking means for the crowding mechanism is defined as such an arrangement or combination of mechanism which will cause the crowding mechanism to be locked and the reversing devices to assume such a position as to disconnect the source of power from the crowding mechanism and vice versa, the parts cooperating as a unitary arrangement as distinguished from separate devices for operating the locking means for the crowding mechanism and the reversing devices therefor.

The boom 5 is capable of adjustment and of slight movements relatively to the platform and it is desirable that means should be provided for so connecting the shaft 16 with the crowding shaft on the platform and with the shipper-shaft on the boom as to prevent binding or breakage due to such movement of the boom. To this end the

shaft 16 is formed in two parts which are provided with a telescoping connection, as shown at 163, whereby the shaft can expand and contract longitudinally to accommodate itself to any movement of the boom relatively to the platform about the horizontal axis of the boom. Further, on each side of the telescoping connection the shaft is provided with a universal joint 164, which 10 enables the telescoping connection to remain in alinement and also take care of any lateral displacement of the boom.

While the several mechanisms may be mounted on the platform in any suitable 15 manner we have, for the purpose of compactness and rigidity of construction, used a frame comprising side members 165 having bearings for each of the several operating shafts. In this manner the shafts are 20 rigidly held in their proper relation one to the other and the frame occupies a much smaller amount of space than would be occupied by separate bearing brackets or frame members.

25 The operation of the mechanism will be readily understood from the foregoing description of the several parts thereof and it will be apparent that the device as a whole is of a very compact arrangement, is simple 30 in its construction and that the various parts thereof are of a durable character. Further, it will be apparent that the various operating mechanisms are so controlled that they are enabled to function in substantially the 35 same manner that they function when driven by individual steam engines, this latter being due both to the general arrangement of the mechanism and to the character and detail construction of the various controlling devices.

40 It will be seen that the reversing shaft 38 can reverse the direction of rotation of the several parts of the machinery but it is provided primarily for the purpose of reversing the propelling mechanism. As will be noticed this reversing shaft carries a clutch at each end, the direction of rotation of which and, consequently, the direction of rotation of all the shafts depending upon which of 45 the two clutches is set. During the digging operation of the shovel the lever 69 for operating the clutches of the reversing shaft is thrown forward and kept in that position, thereby giving the proper rotation to the 50 machinery for hoisting, swinging and crowding and for the forward propelling movement. Of course, the greater part of the time, at least 95 per cent., is consumed during the digging operation. With the 55 lever 69 thrown ahead the operator soon becomes accustomed to the proper direction of throw for the operating levers. Then in case a reverse motion is desired on the propelling mechanism the lever 69 is thrown

65 back and the propelling lever handled in the same manner as for the forward movement thereof. The reversing shaft is not the cause of any confusion to the operator as the lever actuating the clutches on the reversing shaft is always thrown ahead during 70 the digging or major part of the operation and the operator readily becomes accustomed to the proper direction of throw for the other levers. Independent reversing mechanism is provided for the swinging 75 and crowding mechanism. As was stated above, the reversing shaft is also necessary in connection with the hoist or drum, as this is the only means by which the hoisting drum can be reversed if this should be desired for any purpose, such as unwinding the cable or making adjustments.

80 By the above described arrangement we have provided mechanism for an excavating machine which is very simple in its arrangement, compact and economical. It will be noticed that we have provided independent reversing clutch devices for both the crowding and the swinging mechanism. We have 85 also provided a simple clutch for the hoisting mechanism and for the propelling mechanism, these latter mechanisms being 90 reversed by reversing the rotation of the shaft 38.

95 While we have shown and described one embodiment of the invention it will be understood that this has been chosen for the purposes of illustration only, and that we do not desire to be limited to the details of construction shown and described, for obvious 100 modifications will occur to a person skilled in the art.

Having thus fully described our invention, what we claim as new and desire to secure by Letters Patent, is:—

105

1. In an excavating machine, propelling mechanism, an excavating member, crowding mechanism for said excavating member, hoisting mechanism for the same and swinging mechanism therefor, a motor having a 110 shaft adapted to rotate continuously in one direction and operatively connected to said mechanisms, a reversing means interposed between said mechanisms and said motor, and additional reversing means for said 115 swinging mechanism and said crowding mechanism, said hoisting mechanism and said propelling mechanism being reversible by said first-mentioned reversing means.

2. In an excavating machine, a motor having a shaft adapted to rotate in one direction, hoisting mechanism, propelling mechanism, said mechanisms being operatively connected to said motor, clutches to so operatively connect each of said mechanisms to 125 said motor, and reversing devices interposed between the said mechanisms and said motor, whereby either mechanism may be

connected to said motor and when so connected the direction of movement thereof can be reversed.

3. In an excavating machine, a plurality of mechanisms for operating the various parts thereof, a motor provided with a shaft rotatable in one direction, a transmission system interposed between said mechanisms and said motor, each of said mechanisms being provided with means for connecting and disconnecting the same to said transmission system, and means common to all of said mechanisms for connecting and disconnecting the motor therefrom and for reversing the direction of motion.

4. In an excavating machine, a truck, a platform mounted on said truck, a boom, an excavating member mounted on said boom, crowding and hoisting devices for said excavating member, an engine having a shaft adapted to rotate continuously in one direction, a reversing shaft operatively connected with said engine shaft, operative connections between said reversing shaft and said hoisting and crowding mechanisms, yieldable clutch mechanisms mounted on said reversing shaft to control the direction of rotation thereof and to prevent said engine from being choked down by an overload.

5. In an excavating machine, a truck, a platform mounted on said truck, a boom, an excavating member mounted on said boom, crowding and hoisting devices for said excavating member, an engine having a shaft adapted to rotate continuously in one direction, a reversing shaft operatively connected with said engine shaft, swinging mechanism for said boom, propelling mechanism for

said truck, operative connections between said crowding, hoisting, swinging and propelling mechanism and said reversing shaft, means for reversing the direction of rotation of said reversing shaft, and means for controlling said mechanisms independently of said reversing means.

6. In an excavating machine, a motor, a reversing shaft operatively connected to said motor, means for reversing the direction of rotation of said shaft, swinging mechanism, an operative connection between said swinging mechanism and said reversing shaft, means for controlling the direction of movement of said swinging mechanism, hoisting mechanism, said hoisting mechanism comprising a shaft operatively connected through a portion of said swinging mechanism with said reversing shaft, and a drum mounted thereon and means for connecting and disconnecting said drum with reference to said hoisting shaft, propelling mechanism operatively connected to said hoisting shaft, means for connecting and disconnecting said propelling mechanism with reference to said hoisting shaft, crowding mechanism operatively connected to said hoisting shaft, and reversing means for said crowding mechanism.

In testimony whereof, we affix our signatures in presence of two witnesses.
